[57] **CLAIM**

The ornamental design for a spare key holder or similar article, as shown and described.

DESCRIPTION

FIG. 1 is a top plan view of a spare key holder showing my new design;

FIG. 2 is a side elevational view thereof;

FIG. 3 is an end elevational view thereof;

FIG. 4 is a bottom plan view thereof;

FIG. 5 is a top plan view of an alternative embodiment of the spare key holder;

FIG. 6 is a side elevational view thereof;

FIG. 7 is an end elevational view thereof;

FIG. 8 is a bottom plan view thereof;

FIG. 9 is a top plan view of another embodiment of the spare key holder;

FIG. 10 is a side elevational view thereof;

FIG. 11 is an end elevational view thereof;

FIG. 12 is a bottom plan view thereof; and

FIG. 13 is an enlarged scale cross-sectional view taken along line 13—13 of FIG. 9.
